MASSAGE DEVICE

Victor H. Anderson, East Orange, N. J.

Application January 15, 1934, Serial No. 706,742

3 Claims. (Cl. 128—57)

This invention relates to a massage device especially adaptable for use on various parts of the human anatomy and also to be employed for strengthening a person's grip, and has for the 5 primary object the provision of a device which may be set on the floor or on a support to permit a person to easily move the feet or hands backwardly and forwardly thereover to produce a massaging effect to the feet or hands for stimulating the circulation of the blood and to 10 strengthen the muscles and also may be readily folded for use in the hand so that it may be moved over the body, legs and arms for the same stimulating effect to the blood and muscles and when 15 folded may be easily carried or stored in a small space so that a person when travelling may have the same for use at any time desired.

With these and other objects in view this invention consists in certain novel features of construction, combination and arrangement of parts 20 to be hereinafter more fully described and claimed.

For a complete understanding of my invention, reference is to be had to the following description and accompanying drawing, in which 25

Figure 1 is a top plan view partly in section illustrating a massage device constructed in accordance with my invention.

Figure 2 is a side elevation illustrating the same.

Figure 3 is a detail sectional view taken on the line 3—3 of Figure 1.

Figure 4 is a side elevation showing the device in a folded position.

Figure 5 is a perspective view illustrating a 35 spring.

Referring in detail to the drawing, the numeral 1 indicates end members to which are secured ears 2 and the ears of each end member are connected by a shaft 3 rotatably supporting sleeves 4 that extend into the bore 5 of a roller 6. The sleeves 4 have collars 7 integral therewith which abut the ends of the roller 6. The rollers 6 parallel the end members 1 and are shaped to provide hand grips which may be grasped by the hands 45 of a person for the purpose of strengthening the person's grip and also may be employed as handles for using the device for massaging the body, arms and legs.

Secured to the ears 2 by the shafts 3 are arms 50 8 and said arms are hingedly connected by having a shaft 9 extending therethrough. The ends of the shaft are threaded to receive wing nuts 10 adapted to be turned against the overlapping ends of the arms 8. The adjacent ends of the 55 arms are offset to form ears 11 adapted to have

abutting engagement with each other when the arms are positioned, as shown in Figure 1, to prevent pivotal movement of said arms during the use of the device when massaging the feet or hands. Mounted on the shaft 9 are sleeves 12 which extend into the bore of an intermediate roller 13, the latter being preferably constructed of sections tapering towards their adjacent ends. The sleeves 12 are flanged, as shown at 14, to abut the ends of the roller 13.

Brackets 15 are mounted on the shaft 9 and extend in opposite directions from said shaft for rotatably supporting shafts 16 on which are journaled rollers 17 each including a series of sections, said sections tapering, as shown in Figure 1. The rollers 17 are of a greater length than the roller 13. The device when positioned as shown in Figure 2, the rollers 17 and 13 project above the rollers 6 and with the device positioned upon the floor a person may move the foot backward and forward over the rollers thereby massaging the foot to stimulate the circulation of blood and to strengthen the muscles which aids in curing foot troubles, such as fallen arches. The device positioned upon a table or like support the 20 person may move the hands backward and forward over the rollers providing to the hands a stimulating effect to the blood and strengthening the muscles. The device is provided with anti-slipping strips 18 secured to the end members 1 to prevent the device from slipping when placed on a floor or support.

To employ the device for massaging the body the wing nuts are released and the end members swung towards each other and the wing nuts again tightened. The person may then readily grasp the rollers 6 and move the device over the body with the rollers 13 and 17 in contact with the body. This will provide to the body a stimulating effect to the blood and also materially 35 strengthen weakened muscles. The device when folded as described will permit the storing of the device in a comparatively small space. The wing nuts may be left loose and the device in the folded position may then be moved over the body, arms 40 or legs with an oscillatory movement.

A spring 19 may be applied to the device, as shown in Figure 4, for the purpose of tensioning the arms 8 when in a folded position so that the device may be employed for strengthening the 50 grip of a person, it being understood that the person grasps the rollers 6 in one hand and by contracting that hand against the action of the spring 19 the grip will be readily strengthened. When the device is not employed in this manner 55

one end of the spring 18 may be disconnected from its respective arm 8 so as to render the spring inoperative.

Having described the invention, I claim:

- 5 1. A massage device comprising spaced rollers, supporting means forming journals for the rollers and including a shaft, pairs of arms having adjacent ends thereof journaled to the shaft and located outwardly of the ends of said rollers, means on said shaft to releasably secure the arms for movement towards and from each other, means formed on the adjacent ends of said arms to abut for limiting the movement of the arms away from each other, and combined hand grips 10 and support engaging means connected to the arms.
- 10 2. A massage device comprising spaced rollers, supporting means forming journals for the rollers and including a shaft, pairs of arms having adjacent ends thereof journaled to the shaft and located outwardly of the ends of said rollers, means on said shaft to releasably secure the arms for movement towards and from each other, means formed on the adjacent ends of said arms to abut for limiting the movement of the arms away from each other, shafts journaled to the arms, 15 support engaging elements mounted to the second-named shafts, and roller type hand grips journaled to the second-named shafts.
- 15 3. A massage device comprising spaced rollers; supporting means forming journals for the rollers and including a shaft, pairs of arms having adjacent ends thereof journaled to the shaft and located outwardly of the ends of said rollers, means on said shaft to releasably secure the arms for movement towards and from each other, means formed on the adjacent ends of said arms to abut for limiting the movement of the arms away from each other, shafts journaled to the arms, 20 support engaging elements mounted to the second-named shafts, roller type hand grips journaled to the second-named shafts, and spring means mounted to the first-named shaft and detachably connected to said arms and acting to urge said arms away from one another when connected thereto.

VICTOR H. ANDERSON.
